UNITED STATES PATENT OFFICE.

ELMER L. KNOEDLER, OF GLOUCESTER CITY, NEW JERSEY, ASSIGNOR TO WELSBACH LIGHT COMPANY, OF GLOUCESTER CITY, NEW JERSEY, A CORPORATION OF NEW JERSEY.

APPARATUS FOR THE MANUFACTURE OF INCANDESCENT MANTLES.

1,157,555.

Specification of Letters Patent.

Patented Oct. 19, 1915.

Application filed September 30, 1913. Serial No. 792,583.

To all whom it may concern:

Be it known that I, ELMER L. KNOEDLER, a citizen of the United States, residing at Gloucester City, Camden county, State of New Jersey, have invented a new and useful Improvement in Apparatus for the Manufacture of Incandescent Mantles, of which the following is a full, clear, and exact description, reference being had to the accompanying drawings, forming part of this specification, in which—

Figure 1 is a side elevation of a machine embodying my invention; Fig. 2 is a side view of a portion of the machine on a larger scale; Fig. 3 is a partial transverse section of the machine taken adjacent to the muffles; Fig. 4 is a detail view partly in vertical section and partly in side elevation, and showing means for effecting a step-by-step movement of the carrier; Fig. 5 is a section on the line V—V of Fig. 4; Fig. 6 is a vertical section of one of the muffles and also showing its support; Figs. 7 and 8 are detail sectional views taken at right angles to each other and showing the means for effecting dipping of the mantles.

My invention has relation to apparatus for the manufacture of incandescent gas mantles and more particularly to apparatus for effecting the preliminary burning, the hardening and shaping and the dipping of the formed mantles. It also relates more particularly to apparatus of this character in which the hardening and finishing is effected in muffles of the character described and claimed in my copending application Serial No. 749,655, filed February 20, 1913. These muffles are adapted to receive and contain the mantle during the hardening operation, and they are so constructed, as more fully described in said application, as to regulate the escape of the products of combustion from the hardening burners in such a manner as to form between the inner wall of the muffle and the mantle a resistant cushion of the products of combustion against which the mantle is shaped. This intervening cushion of hot gases holds the mantle entirely out of contact with the muffle and enables a very complete oxidation to take place in the mantle.

The present invention is designed more especially to provide a machine or apparatus which is wholly automatic in its char-

acter; that is, in which after the mantles are once on the machine, they are automatically moved from the preliminary burning station to the hardening and shaping station, and from the hardening and shaping station to the dipping and drying stations. The invention provides a machine or apparatus of this character by means of which a large number of mantles may be simultaneously operated upon in a highly efficient and economical manner.

Referring to the accompanying drawings, in which I have illustrated one form of machine or apparatus for carrying out my invention, the numeral 2 designates an endless carrier which may be, in general, of any suitable construction and which is carried by the wheels 3 at opposite ends of the machine. In the drawings, I have shown this carrier as having a series of traveling wheels 5, which travel on tracks 6, carried on the frame of the machine. This carrier is provided with a plurality of pins or studs 7 for engagement with mantle-supporting trays 8. These trays consist of a suitable frame adapted to extend transversely from one side member of a carrier to the other, and having suitable holes at its end portions for engagement with the pins or studs 7. Each tray has seats for removable mantle-supports 9, of the form best shown in Fig. 8, the support consisting of a ring adapted to rest loosely on one of the seats 10 of the carrier and to engage the mantle by its usual supporting legs 11.

The carrier 2 is given a step-by-step movement by means of suitable gearing. In the machine shown, there is a longitudinal main shaft 12, driven by a pulley 13, and carrying a worm 14, which meshes with and drives a worm wheel 15. The shaft of this worm wheel has fixed thereto a cam 16 (see Fig. 4) which is adapted for contact with a roller 17 on a lever 18, pivoted at its lower end to the frame at 19. The upper end portion of this lever is connected by a link 20 with a reciprocating member 21. The member 21 is mounted for reciprocation on a suitable guide 22, fixed to the frame of the machine (see Fig. 5). Pivoted to the member 21 at each side is a dog or pawl 23. These pawls are normally pressed upwardly by means of springs 24, into a position to engage, upon forward movement of the

member 21, with the projecting ends 25 of the pins which connect the links of the carrier chains. While in the drawing I have only shown a reciprocating member 21 in connection with one of the carrier chains, a similar device is provided in connection with each of them, the worm wheel shaft having two of the cams 16 for the simultaneous actuation of the actuating devices at both 10 sides.

When the high portions 16^a of these cams engage the levers 18, the latter will be moved to move the members 21 to the right the required distance to give the desired movement to the carrier. 15

Attached to each member 21 is a pull-back weight 26, which will immediately return the members 21 to their initial positions, after the high portions of the cams have ceased to contact with the levers 18. During this backward movement, the pawls 28 are inactive. 20

The numeral 27 designates the burners for effecting the preliminary burning of the mantles, and 28 and 29 the gas and air supply pipes, respectively, for supplying these burners. 25

30 designates the muffles, in which the hardening and shaping takes place. As shown in detail in Fig. 6, these muffles have open tops and closed perforated side and bottom walls, the combined area of the perforations and their arrangement being such as to permit of the escape of a portion of the products of combustion, but to retain therein a sufficient quantity of the gases to form a separating cushion between the mantles and the walls of the muffles. A series of these muffles is mounted transversely 35 underneath the path of the upper portion of the carrier 2 a short distance beyond the burners 27. They are carried on a vertically movable frame or yoke 31, see Fig. 3. This frame or yoke 31 is mounted for vertical reciprocation in suitable guides 32, so that they can be moved upwardly in a position to cause the muffles to envelop the series of mantles on one of the trays, while the hardening and shaping is taking place, and to be lowered away from the mantles after this 40 operation is completed. For this purpose, I have shown the shaft 12 as provided with a worm 33, meshing with the worm wheel 34, on the transverse shaft 35. Secured to 45 this shaft 35 is a cam 36, which contacts with a roller 37 on the frame or yoke 31. This is best shown in Figs. 2 and 3. While the roller 37 is on the high portion of the cam, the frame or yoke 31 will be held in raised position, but is lowered when the roller 37 passes on to the low portion of the 50 cam.

The numeral 38 designates the hardening burners, 39 the gas supply head for the series of burners, and 40 the air supply head. 55

41 designates the main gas supply pipe for the head 39, and 42 indicates a pilot light supply connection.

In order to secure uniformity in the hardening and shaping action, it is desirable that the gas and air supply for the burners 38 shall be uniform so that the same action will occur at each burner. It is also desirable that the regulation of the gas and air supply shall be independent of the operator and 70 shall be automatically effected so that the supply may be correct at all times. For this purpose, the shaft 12 is provided with a third worm 43, which drives a worm gear 44 on a transverse shaft 45. Secured to the 80 shaft 45 is a cam 46, which contacts with a roller 47, carried by a lever 48, which is attached to the stem of a valve 49, which controls the supply of gas passing through the pipe 41. The lever 48 is weighted, as shown 85 at 50. While the roller 47 is engaged by the high portion of the cam 46, the valve will be held open to the proper extent, but as soon as the roller 47 passes under the low portion of the cam, said valve is closed by 90 the action of the weight 50. The air supply pipe at the opposite side of the machine may have a similar valve, actuated by another similar cam on the shaft 45.

After the mantles have been hardened and 95 shaped in the muffles, they are given the usual dipping in a bath of collodion. For this purpose, I provide the transversely arranged tank 51, which contains the collodion solution and which is mounted to be raised 100 and lowered relatively to the carrier 2, so as to immerse the series of mantles in the bath and then withdraw them therefrom. The tank 51 is mounted upon the vertically 105 movable support 52 (see Figs. 1, 7 and 8) and is actuated by means of a cam 53 on a shaft 54. The shaft 54 carries a worm wheel 55, meshing with a fourth worm 56 on the main shaft 12. After being collodionized and given an opportunity to drain, the series 110 of mantles pass into a suitable drying box 57, which may be heated by means of steam pipes 58 or in any other suitable manner.

The operation of the machine will be readily understood from the foregoing. The operator places a series of mantles on one of the trays. This tray is then placed upon the carrier 2 and is carried forward to the preliminary burning station where the movement of the carrier is halted long enough to enable this preliminary burning operation to take place. While this is being done, the mantles on a preceding tray are being hardened and finished in the muffles, on another preceding tray they are 120 being collodionized, and on still other preceding trays they are being drained and dried. In this manner, each tray with a series of mantles is successively moved from one station to another, the operation being 125 130

entirely independent of manual interference from the time the tray is placed upon the carrier to the time it is removed after passing out of the drying box or oven. The 5 various controlling cams are, of course, so set relatively to each other as to cause the operations which they effect to be properly timed.

The advantages of my invention will be 10 apparent since it provides a very simple machine by means of which a large number of mantles may be simultaneously operated upon. The operation of the machine being automatic, a highly uniform product is obtained, since each mantle is treated under 15 precisely the same conditions and for like periods of time. The hardening and shaping in the muffles or crucibles also gives a very highly uniform character to the 20 mantles.

It will be obvious that various changes may be made in the details of construction and arrangement of the parts. Thus, any suitable trays or racks for holding the 25 mantles may be employed; the details of the carrier may be changed; the actuating gearing may be of any suitable character; instead of using separate air and gas supply pipes, pressure gas may be employed; and 30 various other changes may be made without departing from the spirit and scope of my invention as defined in the appended claims.

The features of the apparatus herein shown and described, but not claimed, form 35 the subject matter of my copending application, Serial No. 792,582, filed September 30, 1913.

I claim:

1. Apparatus for the manufacture of 40 mantles, comprising a traveling carrier, a plurality of burners above the carrier, a plurality of muffles below the carrier, a separate vertically movable support on the carrier for each mantle to be treated, and 45 means for raising each muffle into contact with a support on the carrier to thereby raise the mantle to the action of a burner, the muffles having means which coöperate with said supports to center and carry them 50 when so raised, substantially as described.

2. Apparatus for the manufacture of

mantles, comprising parallel carrier chains having rollers, tracks for said rollers and forming supports for said chains, a plurality of transverse mantle carrying bars 55 connecting the chains, and each having a plurality of seats for mantle supports, and mantle supports arranged to be loosely mounted in said seats, substantially as described. 60

3. Apparatus for the manufacture of mantles, comprising parallel carrier chains having rollers, tracks for said rollers and forming supports for said chains, a plurality of transverse mantle carrying bars 65 connecting the chains and each having a plurality of seats for mantle supports, mantle supports arranged to be loosely mounted in said seats, a plurality of vertically movable muffles below the transverse 70 mantle carrying bars, and means for raising said muffles around the mantles and into lifting engagement with the mantle supports, substantially as described.

4. In apparatus for manufacturing mantles, the combination with parallel carrier chains, tracks for supporting said chains, transverse mantle carrying bars connecting the chains, and means for imparting a step by step movement to said chains 75 comprising reciprocating gripping devices having means for engaging and moving the chains at intervals in one direction, substantially as described.

5. Apparatus for hardening and shaping 85 mantles, comprising parallel carrier chains, means for imparting a step by step movement to said chains, a plurality of transverse mantle carriers having means for detachably engaging the chains, each of said 90 carriers having seats for a plurality of separate mantle supports, together with a plurality of vertically movable muffles, and means for raising said muffles into lifting engagement with the mantle supports, sub- 95 stantially as described.

In testimony whereof, I have hereunto set my hand.

ELMER L. KNOEDLER.
